US00D591264S

(12) **United States Design Patent**
Hong et al.

(10) **Patent No.:** **US D591,264 S**
(45) **Date of Patent:** **** Apr. 28, 2009**

(54) **EARPHONE**

(75) Inventors: **Fu-Long Hong**, Taoyuan County (TW); **Hsiao-Chuan Huang**, Taoyuan County (TW); **Yi-Bin Ho**, Taoyuan County (TW); **Hung-Yi Huang**, Taoyuan County (TW); **Hung-Yu Chen**, Taoyuan County (TW); **Meng-Sheng Chiang**, Taoyuan County (TW); **Po-Lin Ho**, Taoyuan County (TW)

(73) Assignee: **HTC Corporation**, Taoyuan County (TW)

(**) Term: **14 Years**

(21) Appl. No.: **29/321,873**

(22) Filed: **Jul. 24, 2008**

(30) **Foreign Application Priority Data**

Mar. 31, 2008 (TW) 97301886

(51) **LOC (9) Cl.** **14-01**

(52) **U.S. Cl.** **D14/205**

(58) **Field of Classification Search** ..... D14/205, D14/206, 223, 137, 142, 192, 217, 218; D13/133, D13/173, 154, 147; D3/215, 224/220, 250, 224/257, 258; 379/420.01–420.04, 433.03, 379/438; 174/36, 138 F; 455/90.1, 569.2, 455/575.2, 351; 24/122.6

See application file for complete search history.

(57) **CLAIM**

The ornamental design for an earphone, as shown and described.

DESCRIPTION

FIG. 1 is a perspective view of an earphone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures are for illustrative purposes only and do not form part of the claimed design.

CERTIFICATE OF CORRECTION

PATENT NO. : Des. 591,264 S
APPLICATION NO. : 29/321873
DATED : April 28, 2009
INVENTOR(S) : Fu-Long Hong et al.

Page 1 of 4

It is certified that error appears in the above-identified patent and that said Letters Patent is hereby corrected as shown below:

The title page should be deleted and substitute therefor the attached title as shown on the attached page

Replace Figs. 2 and 3 with the attached Figs. 2 and 3 as shown on the attached pages

Signed and Sealed this

Eighth Day of September, 2009

David J. Kappos
Director of the United States Patent and Trademark Office
